ANTENNA SYSTEM FOR SHORT WAVES

Lester C. Van Atta, Winchester, Mass., assignor,
by mesne assignments, to the United States of
America as represented by the Secretary of the
Navy

Application October 25, 1943, Serial No. 507,585

15 Claims. (Cl. 250—33.65)

1

This invention relates to radio antenna systems, and particularly antenna systems for operation on "micro" wave lengths, including an antenna, a small reflecting element located near and forwardly of said antenna and a large reflector at a greater distance from said antenna and located rearwardly of it.

Directive antenna systems for "micro" wave lengths, which is to say for wave lengths less than about 50 centimeters, have in the past made great use of parabolic reflectors which are able to give a high degree of directivity. Parabolic reflectors are also fairly readily adapted for aiming in different directions and may when suitably mounted be moved about rapidly and conveniently without appreciable distortion of the directivity of the beam produced. In order to realize the full advantage of a parabolic reflector it is important that the paraboloid be properly illuminated at all times, which is to say that the antenna system associated with the parabolic reflector should radiate as much as possible in the direction of the paraboloid and as little as possible in other directions, especially directions at wide angles to the axis of the parabolic reflector.

A metallic sheet reflector in front of the antenna is sometimes used for the purpose of cutting off all direct forward radiation of the antenna and reflecting such radiations back into the parabolic reflector. Various shapes of sheet metal reflectors have been used. A circular disk somewhat less than one wave length in diameter has been found to be the most effective and suitable of such arrangements. Such a disk should be placed approximately a quarter-wave length in front of the antenna, and preferably slightly more than a quarter-wave length, for instance about 0.27 wave length. In such an arrangement the effective center of radiation of a combination of a dipole antenna and a reflecting disk usually lies midway between the dipole antenna and the reflecting disk. In some cases it may lie closer to the reflecting disk than such midpoint. The location of the effective center of radiation can be determined experimentally with sufficient accuracy for antenna design information. Such determination may make use of measurements and plots of phase patterns in the neighborhood of the system, from which the location of the effective center can be deduced.

An ultimate object of this invention is to provide a steerable directive antenna system for microwave lengths providing a more concentrated and powerful beam than has heretofore

2

been possible for a given transmitter power and paraboloid reflector diameter. Particular objects of this invention include production of an antenna with an improved radiation pattern (with regard to side lobes, beam width, etc.), the provision of an antenna which is properly matched to the feed line associated therewith so that there will be maximum transfer of energy to the transmitted beam, and the provision of means for illuminating a parabolic reflector with microwave radiation more effectively than in the previous practice.

The invention is illustrated in the accompanying drawings in which:

15 Fig. 1 is a side view, partly in section, showing the preferred form of antenna systems in accordance with this invention;

20 Fig. 2 is a sectional view showing in detail the construction of the forward part of the antenna system of Fig. 1;

25 Fig. 3 is a perspective view of another form of antenna system according to this invention, the parabolic reflector being omitted for convenience, and

30 Figs. 4, 5, and 6 are diagrams of radiation patterns that are believed to correspond to certain antenna systems herein described and which are provided for elucidation of the principles believed to control the operations of antenna systems according to this invention.

35 I have found that highly satisfactory illumination of parabolic reflectors for the purpose of forming a concentrated beam of radiation can be obtained with a parasitic dipole reflector, sometimes known as a "dummy," in front of the antenna proper instead of a sheet or disk reflector provided the "dummy" is properly spaced. Although fair concentration of the radiated beam can be achieved with such a dipole located one quarter-wave length in front of the antenna dipole, the directional properties of the beam are greatly improved if the parasitic reflector dipole is spaced considerably closer to the antenna proper than one quarter-wave length, and preferably one eighth-wave length. This is especially true if at the same time the distance between the midpoint of the antenna-parasitic-reflector system to the vertex of the parabolic reflector is properly adjusted as hereinafter described. I have also provided certain other improvements, further described below, which are adapted to be used together with the features just mentioned, although they are also capable of independent use.

50 In the preferred form of antenna illustrated

in the drawing the parasitic reflector 3 is supported on a projection 4 inside a thin bulb 4a of high quality insulating material, such as polystyrene, which serves to exclude moisture and dust and may also serve to maintain atmospheric or higher pressure to prevent the occurrence of corona discharges when the apparatus is used at high altitudes. The antenna dipole 1, 2 is fed by a coaxial feed line 5 and is provided with rounded arms 1 and 2, these arms being rounded primarily to reduce corona. It will be noted that the dipole 1, 2 is at right angles to the axis of the feed line 5. This configuration is preferred because it permits introducing the feed line through the vertex of the parabolic reflector and supporting the feed line and dipoles at the said vertex, thus keeping the feed line symmetrical with respect to the parabolic reflector, which is a great advantage in obtaining a concentrated beam of radiation and a good directional radiation pattern. If for some reason the advantages resulting from the symmetrical location of the feed line with respect to the parabolic reflector can be dispensed with, other advantages of this invention can of course still be realized with other well-known arrangements of the feed line with respect to the dipoles and the parabolic reflector.

In order to provide better support of the feed line and antenna system from the vertex of the parabolic reflector the outer conductor of the feed line 5, as shown on Fig. 1, is progressively thickened as it approaches the parabolic reflector, which is shown at 6, so that the outer surface of the feed line 5 has a flaring shape. The feed line and its associated antenna system is fastened to the parabolic reflector 6 by a suitable clamping or bolting device, a simple form of which is shown on Fig. 1 in the form of a shaped washer 8 and a nut 9 cooperating with a shoulder 10 forming part of the feed line body; or the feed line may enter through a slot or hole in the reflector when the latter is to be moved with relation to the antenna proper. The end of the feed line on the outside of the parabolic reflector 6 is shown threaded at 11 for receiving a coupling for the purpose of connecting it to a further section of line or a rotating joint forming part of the transmission and reception system with which the antenna system is designed to be employed.

The effective center of radiation of the system comprising the dipole 1, 2 together with its parasitic reflector dipole 3 is the midpoint between the centers of the respective dipoles. Heretofore it has been customary to locate the effective center of the illuminating source at the focus of the parabolic reflector for the formation of a directive beam of radiation, irrespective of the relation between the focal length and the wave length in question. I have found that it is more important to locate the effective center of radiation at a point separated from the vertex of the parabolic reflector by an integral number of half-wave lengths than to take care to locate the effective center of radiation exactly at the focus. I therefore preferably locate the effective center of radiation at that number of half-wave lengths from the vertex of the parabolic reflector which brings the effective center of radiation nearest to the focus, which is to say that in the apparatus of Fig. 1 the dimension *a* should be equal to

$$\frac{n\lambda}{2}$$

where λ is the wave length and *n* is the whole number which brings the expression nearest to the focal length of the parabolic reflector.

In cases in which the focus falls approximately half-way between two half-wave points, the effective center of feed should be located at that half-wave point which more nearly corresponds to the subtending of the optimum solid angle at the effective center by the aperture of the parabolic reflector. This will depend on the directivity of the feed (the "feed" being the antenna dipole and auxiliary reflector combination) and on the shape (i. e. focal-length-diameter ratio) of the parabolic reflector. For example, if the parabolic reflector is initially somewhat too deep, the first half-wave point beyond the focus should be chosen. The matter of the most desirable paraboloid shape for antennas of this invention is discussed further below. In any event, of the points at integral numbers of half-wave lengths from the vertex of the parabolic reflectors, one of the two falling closest to the focus is generally to be chosen for the effective center of radiation. If this is done, such effective center will in every case be not more than a half-wave length from the focus. If the nearest point is chosen, the effective center will be at most a quarter wave length from the focus.

Where it is possible to do so, I provide the antenna system with a parabolic reflector the focal length of which is equal to an integral number of half-wave lengths of the radiation in question. It is not always convenient to do so, however, because templates for the manufacture of parabolic reflectors are expensive and it is consequently not economical to manufacture such reflectors in many different focal lengths. The adjustment just described of the dimension *a*, referring to Fig. 1, is especially important where close spacing such as spacing of the order of one eighth wave length, is used between the antenna dipole 1, 2 and the reflector dipole 3, for reasons more fully explained below.

As is more fully explained below in connection with Figs. 4, 5 and 6, the importance of the above considerations in locating the antenna and its associated auxiliary reflector with respect to the paraboloid vertex depends on two factors: (a) the proper phasing of direct forward radiation with radiation reflected from the parabolic reflector and (b) the obtaining of a minimum antenna input impedance in order to "match" the feed line as well as possible to the antenna. It is important that the input impedance of the antenna system be kept low in order that this impedance may be capable of being matched to the feed line by means of a "sleeve" type transformer of practicable dimensions. If the transformer is required to provide a large transformation ratio, excessive frequency-sensitivity may result. When a given system, consisting of a feed line, an antenna and an auxiliary reflector, is once adjusted for impedance match at a point near the focus of a parabolic reflector located on the axis of the latter and an integral number of half-wave lengths from the vertex, it is substantially matched for other such "half-wave point" locations of the same parabolic reflector and also substantially matched, assuming a standing wave power ratio of 1.5 can be tolerated, for such "half-wave point" locations in other parabolic reflectors, irrespective of the focal length of the latter, provided that the original match was obtained in a reflector having a focal length of 1.5 wave lengths or more and that the other reflectors in question also have focal lengths of at least 1.5 wave lengths. For smaller reflectors, the match depends on the focal length. For the

large reflectors, the possibility of change of reflectors without rematching holds also for antenna feeds matched for locations other than the half-wave points, provided the location relative to the half-wave point is maintained when the reflector is changed.

Thus by the use of the relations here disclosed an antenna feed may be designed for effectively illuminating any of a wide variety of beam-forming parabolic reflectors.

Further features of the preferred form of antenna are shown in detail on Fig. 2. As illustrated in that figure a detachable coupling is provided in the feed line 5 at some distance in back of the antenna in order that the antenna may be replaced or removed for adjustment without unfastening the feed line 5 from its support at the vertex of the parabolic reflector (not shown on Fig. 2). The coupling includes a threaded tightening sleeve 15, a threaded bushing 16 mounted on the outer conductor 17 of the feed line 5, a gasket 18 made of a compressible elastic material such as neoprene, a split steel friction ring 19 and a connector plug 20 fitting into recesses 21 and 22 in the respective inner conductors 23 and 24 of the two portions of the feed line. Insulating beads or spacers 25 are shown in the feed line 5 for maintaining the relative positions of the inner conductor 23 and the outer conductor 17. The tubular element 26 forms the outer conductor of the section of coaxial line between the coupling just described and the antenna. It may be conveniently made of machined brass. It is provided with a shoulder 27 and flange 28 which serve respectively for mounting a choke sleeve 29 and for holding in place the inner member or cup 30 of the polystyrene protective bulb about the antenna system. A gasket 31 of compressible material is provided between the flange 28 and the cup 30 for the formation of an airtight seal between the polystyrene bulb and the tubular conductor 26. A metallic sleeve or cup 32 is threaded on the outside of the tubular conductor 26 so that its mouth fits over the outside of the neck of the cup 30, thus holding the cup 30 firmly in place and at the same time providing a radio frequency choke adapted to inhibit the formation of standing waves on the feed line 5. A lock nut 33 is provided for holding the cup 32 in place.

In order that the structure 32 in cooperation with the neck of the cup 30 may act as a choke in this fashion the length of the cup wall (the dimension *b* on Fig. 2) must be carefully adjusted. This length should be such that a quarter-wave length oscillation can be maintained in the cavity formed by the conducting parts, which is to say that the cavity acts as a "closed pipe" type of resonator. Because of the presence of the polystyrene insulation the length of the dimension *b* is considerably less than the quarter-wave length of oscillations of the frequency in question radiating in the open air. It can however be calculated by known means from the dimensions of the structure and the characteristics of the dielectric, or it may be determined experimentally. A more specific value of this dimension is given below together with values of certain other dimensions which have been found suitable for a particular range of wave lengths in an apparatus of the particular configuration of Fig. 2. If the apparatus is to be used at high altitude where the air surrounding the antenna system on the outside of the cup 30 is at a pres-

sure considerably below normal atmospheric pressure, it may be advisable to cement the cup 30 to the structure 32 when the apparatus is assembled to prevent the occurrence of corona in the resonator formed by the structure 32 on account of the occurrence of narrow air spaces inside the structure 32.

The sleeve 29, like the structure 32, cooperates with the tubular conductor 26 to provide a resonator on the outside of the conductor 26 which acts to prevent the occurrence of standing waves on the outside of the conductor 26 and generally on the feed line 5. This resonator is again a quarter-wave resonator with its open end directed towards the antenna. The depth of the cavity should again correspond to an electrical quarter-wave length, which in practice is slightly less than a quarter of the wave length in open air of radiation of corresponding frequency, the variation from the exact quarter-wave length being probably due to "end effects" in the cavity.

The resonator formed by the sleeve 29 may be regarded as a "choke" to suppress standing waves on the outside of the feed line or it may be considered as a balancing resonator providing a transition (i. e. acting as a "transformer," in a sense) between the unbalanced rear portion feed line (one conductor being at "R. F. ground" potential) and the balanced portion feed line near the antenna where both conductors have R. F. voltages with respect to ground. In this sense the resonator permits the forward end portion of the line 5 to behave as a balanced line while the rear portion remains unbalanced as required for normal operation. The distance between the mouth of the choke sleeve 29 and the antenna 1, 2 is quite important since it affects the impedance offered by the antenna system to the feed line. In general the choke should be close to the antenna, preferably considerably less than a quarter-wave length, and as close as the danger of corona discharges will permit under the desired conditions of operation. The exact spacing is not quite so critical for small differences in wave length as some of the other distances here mentioned and the effect of this spacing upon the antenna impedance may be compensated for or taken into account in selecting the proportions for the quarter-wave matching transformer provided as hereinafter described on the inner conductor 24.

The dipole arm 1, formed in a rather bulbous shape for the mitigation of corona and for the reduction of frequency sensitivity, is mounted directly on the end of the tubular conductor 26 as shown, the tubular conductor 26 being cut away on the opposite side at an angle of about 35° (see also Fig. 1) in order to allow ample clearance for the dipole arm 2, which is fastened upon a rounded end piece 35 threaded on the end of the inner conductor 24 of the feed line in such a manner as to embrace the conical insulating bead 36. The dipole arm 2 is preferably of the same shape and size as the dipole arm 1, in order to provide as even a configuration of the potential gradient as possible and thereby inhibit corona discharges. The electrical center of the dipole antenna 1, 2 is not exactly on the axis of the feed line 5, so that it is advisable to align the reflector dipole 3 slightly off-center with respect to the axis of the feed line 5 so that it may be symmetrical with respect to the midpoint of the dipole 1, 2 as shown on Fig. 2. It is not certain that this slight asymmetry results in a similar asymmetry of the effective center of radiation,

because the latter is also affected slightly by the presence of standing waves between the mouth of the choke sleeve 29 and the antenna, which standing waves will in general not be symmetrical with respect to the axis of the feed line, producing an effect which may well outweigh as well as counteract that produced by the mechanical displacement of the dipole with respect to the axis of the feed line. Thus for all practical purposes the antenna system shown in Fig. 2 acts as if its effective center of radiation were on the axis of the feed line and halfway between the axes of the dipole 1, 2 and the dipole 3. The length of the dipole 3 should approximate an electrical half-wave length and is preferably somewhat longer than the dipole 1, 2. The preferred physical dimensions, in terms of the "free space" wave length, are given in the table below.

Keying arrangements 37 are provided for maintaining the insulating bead 36, which is preferably made of high quality polystyrene, in fixed relation to the inner and outer conductors of the feed line. The bead 36 is also preferably provided with a longitudinal groove (not shown) at some point on its outer periphery for the purpose of allowing communication between the atmosphere in the feed line and the atmosphere in the bulb or pressure vessel surrounding the dipoles. Thus at the same time the antenna system and the feed line may be maintained at atmospheric or super-atmospheric pressure for the prevention of sparking and corona. It is to be noted that the end piece 35 is provided with a rounded end surface the shape of which contributes to the prevention of corona discharges.

The inner conductor 24 which is connected to the dipole arm 2 through the conducting end piece 35 is provided with a thickened portion 38, the length of which is shown on Fig. 2 by the dimension *d*. This length is usually approximately a quarter-wave length of the oscillations in question, although other lengths may be used provided a suitable coordination of the spacing between the thickened portion and the antenna is made in accordance with principles well known in the art. The amount by which the diameter of the inner conductor 24 is increased for the length of the thickened section 38 depends not only upon the dimensions of the antenna 1, 2 and the position of the choke sleeve 29 but also rather considerably upon the distance between the thickened portion 38 and the antenna. The desirable distance between the thickened portion 38 and the antenna will be affected somewhat by the nature and configuration of the insulating bead 36. With proper adjustment of this length (the dimension *e* on Fig. 2) the necessary thickening of the quarter-wave matching transformer 38 may be very small, such as one hundredth of an inch additional radius. In general it should be noted that the antenna impedance is affected by variations in spacing between the antenna dipole and the reflector dipole and also by nearby reflecting objects in the path of the beam cast by the parabolic reflector, so that the matching transformer 38 should be designed with regard to the antenna impedance as it occurs in the service position of the antenna system. The antenna system of Figs. 1 and 2 constructed as herein described and mounted without obstructions in the path of the beam cast by the parabolic reflector has an input impedance of not very much greater than the characteristic impedance of the feed line 5 which may be about 50 ohms, so that only a small thickening of the

inner conductor 24 will suffice to provide a suitable impedance match.

In an apparatus of the particular type shown in which apparatus the inner diameter of the outer feed line conductor was between $\frac{1}{8}$ and $\frac{1}{4}$ wave length, good results have been obtained with the distance *e* almost exactly equal to a quarter of the free-space wave length. The electrical wave length in question is greater and may be nearer a half than a quarter of the wave length on account of the insulating bead 36. The antenna input impedance at the point of feed is slightly inductive in the particular apparatus shown in Figs. 1 and 2 when constructed as herein described for wave lengths between 9 and 10 centimeters, but this effect is to some extent compensated by the capacitive loading resulting from the location of the insulating bead 36 between the inner and outer conductor.

20 The design of matching transformers consisting of a quarter-wave section of transmission line of a characteristic impedance different from that of the line to which it is desired to match a particular load impedance is well understood. 25 The determination of the impedance of the load is not always so simple, particularly at microwave frequencies. Techniques have recently been evolved however for making this determination, and one of the most practical of these makes 30 use of the measurement of the standing wave ratio resulting from the connecting of the load impedances in question to a line of known characteristic impedance. Such a determination will provide a basis for calculating the desired dimensions 35 of matching transformer and its location in the line. The accuracy of the calculation can then be checked by another measurement of standing waves with the transformer in the line. The nature of the error will indicate the proper direction for correction of the dimensions of the transformer.

In general, the characteristic impedance of the quarter-wave matching section of line should be equal to the geometric mean of the characteristic impedances of the line and of the load, as is well known in the art. The desired characteristic impedance may be obtained in the quarter-wave section by varying the dimensions of the conductors or the dielectric constant of the medium (i. e., by varying the medium) between them, or both. The characteristic impedance Z_0 of a coaxial line depends on the cross-sectional dimensions of the line as follows:

$$Z_0 = 138 \log_{10} \frac{b}{a}$$

where *b* is the inner diameter of the outer conductor and *a* is the outer diameter of the inner conductor.

60 The polystyrene cup 30 is closed by another cup-like member 40 preferably made of the same material to form an airtight vessel or bulb about the dipoles. The cups 30 and 40 are put together by a close-fitting joint 41 where they are preferably cemented together by polystyrene cement. Such a cemented joint will hold at all reasonable pressure differentials between the inside and outside of the bulb. No observable effect on the 65 radiation pattern of the antenna system has yet been traced to the presence of the polystyrene enclosure on antenna systems constructed in accordance with Figs. 1 and 2 with reasonably thin bulbs. The cup 40 is provided with a central 70 protuberance 42 upon which is mounted a mem-

ber 43 made of similar insulating material which is adapted to hold in place the reflector dipole 3 in cooperation with a kingpin 44. The member 43 is adjusted and dimensioned suitably for holding the reflector dipole 3 at the proper spacing from the antenna dipole 1, 2 for the wave length in question.

In order to give complete details concerning the preferred form of antenna for the purpose of illustrating more fully the way in which the invention is best carried out there are tabulated below certain dimensions relating to the apparatus of Fig. 2 which have been found suitable for operation at wave lengths in the microwave range. When variation of one or more of these dimensions is contemplated, it should be remembered that these dimensions are in general interdependent and the performance with respect to the other dimensions should be checked if one of these dimensions is varied substantially. The dimensions given below relating to the matching transformer 38 have been experimentally checked only for a narrow range of shorter wave lengths, but values for other wave lengths in the microwave range are not likely to be much different, in terms of the wave length, for a similar antenna structure. Since it is convenient within the aforementioned range of wave lengths to keep constant the position of the mouth of the choke sleeve 29, changes in wave length of operation and corresponding changes of the dimensions given below in accordance with wave lengths may require a further adjustment of the matching transformer diameter and location because of a change of antenna impedance. The dimensions given below are expressed in terms of the free space wave lengths and of course apply only if substantial changes in the configuration of spacing insulators such as the bead 36 and the like are avoided. Where the dimension given is a range of values, the first value given represents a value which has been found successful at shorter wave lengths, and the dimension last given represents a value that has been found successful at longer wave lengths. The values relating to the matching transformer were obtained with the former values of the other dimensions. The variations are at least partly explained in that the feed line diameters and the choke spacing were held constant while the other dimensions and the frequency were varied.

Table

Dimension	Indication on Fig. 2	Magnitude in Free Space Wave Lengths
Depth of polystyrene-filled choke.....	<i>b</i>	0.128
Depth of inner choke.....	<i>c</i>	0.23
Length of matching transformer.....	<i>d</i>	0.248
Position of matching transformer.....	<i>e</i>	0.249
Length of parasitic dipole.....	<i>f</i>	0.45 to 0.44
Length of antenna dipole.....	<i>g</i>	0.408
Dipole arms.....	<i>h</i>	0.161 to 0.167
Spacing between dipoles.....	<i>i</i>	0.122 to 0.127
I. d. of outer conductor of feed line.....		0.157 to 0.134
O. d. of inner conductor of feed line.....		0.070 to 0.059
Diameter of matching transformer.....		0.084

Fig. 3 shows another form of antenna according to this invention which is suitable for use under conditions in which the protective polystyrene bulb shown in Figs. 1 and 2 may be dispensed with. As in Fig. 2, only the forward part of the antenna system is shown, the parabolic reflector being omitted for convenience of illustration. In this form of the invention the reflector dipole 3 is carried on a yoke 50 which forms an

extension of a tubular sleeve 51 which may be slidably adjusted longitudinally along the outside of the choke sleeve 29. The position of sleeve 51 and its yoke extension 50 may be fixed by means of a set screw 52. The yoke 50 and the sleeve 51 may conveniently be made of conducting material, such as brass, for since the arms of the yoke 50 are in a plane perpendicular to the dipoles, the structure does not interfere with the operation of the choke sleeve 29. This structure, however, may also be formed of insulating material. Except for the omission of the polystyrene protective bulb and its associated parts and for the substitution of the structure 50, 51 for the support of the parasitic dipole 3, the construction of the antenna system shown in Fig. 3 preferably follows that of the antenna system shown in Figs. 1 and 2.

The rounded end of the end piece of the inner conductor 35 of Fig. 2 appears at 53 on Fig. 3. Likewise at 54 is shown part of the surface of the insulating bead shown in cross section at 36 on Fig. 2.

Although it has been determined by experiment that the use of close spacing of the order of one-eighth-wave length between the antenna dipole and the reflector dipole, instead of one-quarter-wave length spacing previously thought to be most desirable, results in better directive patterns for the entire system including a parabolic reflector, it is rather difficult to explain on theoretical grounds why the closer spacing should be superior or even to give an accurate description of just how the parabolic reflector is illuminated by the combination of close-spaced dipoles. It is to be noted at the outset that the requirements of an antenna system for illuminating a parabolic reflector and producing therewith a highly directive beam of radiation are to a large extent determined by the maximum allowable diameter for the parabolic reflector. In a steerable antenna system, and particularly in one which is regularly moved about for purposes of scanning, it becomes rather difficult to handle very large parabolic reflectors and this difficulty is all the greater when the antenna system is to be mounted on seagoing vessels or on aircraft. Consequently the most practical sizes of parabolic reflectors are in the range between 5 and 15 wave lengths, with reflectors with a diameter of about 8 wave lengths being rather commonly used.

The shape most desirable for the parabolic reflector depends to some extent on the directive properties of the feed. Thus, although before this invention it was common practice to use a parabolic reflector with a focal length equal to about 0.35 times the diameter, with the type of feed which I prefer, having a dipole auxiliary reflector about $\frac{1}{8}$ wave length in front of the antenna dipole, I find that a parabolic reflector with a focal length equal to about 0.3 times the diameter is to be preferred. If the illumination of the parabolic reflector is tapered off towards the edge of the reflector, there is some lowering of the gain, but such a tapering off of illumination tends to reduce the amplitude of side lobes, which is an important consideration. In order to obtain a desirable radiation pattern for the entire system including the parabolic reflector, the parabolic reflector should therefore intercept a sufficient solid angle of radiation to provide a somewhat tapered illumination of the parabolic reflector and the antenna "feed" system should radiate very little laterally or in forward directions making substantial angles (such

as 15° or more) with the axis of the parabolic reflector.

The radiation pattern of a dipole antenna provided with a parasitic reflector dipole spaced one-quarter-wave length away is usually represented by a curve such as is shown in Fig. 4. The position of the null corresponds to the direction towards the reflector dipole. The theoretical basis of this representation does not take into account any effect of the presence of the reflector dipole upon the behavior of the antenna dipole itself and it assumes that the reflector dipole radiates energy with a 90° phase difference with respect to the energy radiated from the antenna dipole. It is to be noted that if the reflector dipole is of an electrical length slightly different from that corresponding to a half-wave length, or if some reaction should take place between the two dipoles, the phase of the current excited therein and consequently the phase of the radiation from such reflector dipole may be different from that which would be expected from a reflector dipole of an electrical length of exactly a half-wave length and coupled only by radiation. The foregoing may explain the phenomenon that, as I have found, the spacing between antenna dipole and reflector dipole producing the best beam pattern in connection with a parabolic reflector should be of the order of one-eighth-wave length rather than one-quarter-wave length.

Experiments tend to establish, however, that the radiation pattern of the dipole pair arranged in accordance with this invention with approximately one-eighth wave length spacing between the dipoles is not of the type shown in Fig. 4, but rather of another type, including a principal lobe of radiation and a small oppositely-directed additional lobe of radiation. Fig. 5 is a theoretical diagram of the calculated radiation pattern for a pair of dipoles spaced one-eighth wave length apart and excited with a phase difference of about 155°, the intensity of excitation being equal for the two dipoles. The solid curve represents the pattern in a plane perpendicular to the dipole (the "magnetic plane") and the dotted curve represents the pattern in the plane which includes the axes of the two dipoles (the "electric plane"). The dotted pattern is more directive since it, as calculated, corresponds to the modulation of the magnetic-plane pattern by the characteristic figure 8 radiation pattern of a single dipole in the electric plane.

Fig. 6 illustrates a typical experimentally obtained directive pattern measurement on a pair of dipoles comprising an antenna dipole and a reflector dipole located at one-eighth wave length from the antenna dipole, the dipoles being parallel. The solid curve represents the pattern measured in the magnetic plane and the dotted curve represents the pattern measured in the electric plane. The experimental pattern shown in Fig. 6 corresponds to the calculated pattern shown in Fig. 5 in the existence of sharp nulls in the broad side direction, in the more directive pattern in the electric plane and in the presence of a small lobe in a direction opposite to that of the principal lobe. The possible presence of additional factors not accounted for in the calculated curve is, however, suggested by the irregularities in the experimental curve and in the increased directivity of both the electric and magnetic plane patterns. It is possible that the thickness of the dipoles may be one such factor.

As a result of the small forward lobe of the feed system (the principal lobe being directed

backwards towards the parabolic reflector), the maximum forward gain of the entire antenna system including the parabolic reflector varies rather considerably with the distance between the effective center of radiation and the vertex of the parabolic reflector, and this variation is periodic and provides a maximum forward gain when the aforesaid distance is equal to an integral number of half-wave lengths. This variation in gain is particularly noticeable with parabolic reflectors of small diameter, such as eight wave lengths or less and amounts to a factor of two for a reflector diameter of three wave lengths. The adjustment of the distance between the effective center of radiation and the parabolic reflector in accordance with this invention to produce maximum gain brings the radiation from the forward lobe into phase with the radiation reflected from the parabolic reflector.

A similar direct-forward lobe (sometimes called a "back lobe," with respect to the feed) has been found to be exhibited by systems in which the auxiliary reflector is a sheet metal disk about a quarter-wave length in front of the antenna dipole. This may result from the presence of currents near the edges of the disk. The "half-wave point" location of the effective center of radiation is therefore desirable for such antenna systems, just as it is in the preferred antenna system having a reflector dipole about one-eighth wave length in front of the antenna dipole.

The forward radiation, when properly phased as above described by the location of the effective center of radiation at a "half-wave point," appears to have an additional improving effect upon the directive properties of the entire antenna system resulting from the fact that the direct-forward lobe destructively interferes with the first side lobe of the radiation reflected from the parabolic reflector. The beam formed by the parabolic reflector is narrower than the direct-forward lobe and has a number of side lobes, some of the closer which fall within the angle occupied by the direct-forward lobe. It is known from principles of optics that the first side lobe on each side of the main beam will be opposite in phase to the main beam and that these two side lobes will usually be the most intense of all the side lobes. The direct-forward lobe, thus, at the same time that it adds to the main beam, counteracts the most troublesome side lobes, thus improving the overall directive qualities of the beam.

The amount of defocusing resulting from placing the effective center at or near a "half-wave point" should preferably be kept at a minimum. If possible it would be desirable to provide a parabolic reflector with a focal length equal to an integral number of half-wave lengths.

Antenna systems constructed according to this invention are particularly suitable for steerable directive systems employed for radio echo detection and location service. They may be used either for transmission or reception and indeed also for systems in which transmission and reception is accomplished with the same antenna system. Antenna systems according to this invention provide highly directive beams with narrow beam widths and extremely low side lobe radiation in spite of the fact that the parabolic reflector may have a diameter of only 4 wave lengths or even less. This is a very great advantage for echo detection and locating systems for it is evident that the parabolic reflector,

which according to the preferred form of construction itself supports the feed line and antenna system, may be mounted in such a way that it may be rotated about two different axes, preferably at right angles to each other. The mechanical arrangements of such mountings are well known as they have been used for guns, searchlights and other devices for a long time. It is readily apparent that rotation about both mounting axes can be accomplished simultaneously to produce a scanning of a desired area or, more precisely, of a desired solid angle, just as scanning by rotation about two axes has been performed in the past in the case of optical systems (e. g., for television), lawn sprinklers, and so on. The antenna system of the present invention lends itself readily to construction in a form sufficiently sturdy to enable relatively rapid rotation or other movement of the entire antenna system. If the antenna system and feed is rotated together with the parabolic reflector, of course, some rotating joints will be necessary in the feed line which connects the antenna with the transmitting and/or receiving system. Such joints are now known and have been successfully operated. The arrangement of the feed line and the provision of such joints, although it may be an essential part of a continuously scanning type of radio-echo detection and location apparatus is not of direct concern to the practice or the understanding of this invention, and for that reason is not described in detail here, since it does not affect the formation of a sharply directive beam of radiation. It is, however, to be understood that antenna systems according to this invention have advantages particularly suited for operation in a continuously scanning type of detection and location apparatus. This is especially true with respect to the provision of low side lobe radiation, for side lobe response in a continuously scanning system which employs a cathode ray type of indicator introduces not only distracting signals but also an undesired ambiguity because the indication resulting from the side lobe response cannot be distinguished from an indication produced by the main beam of radiation when pointed in quite another direction.

What I desire to claim and secure by Letters Patent is:

1. A directive antenna system including a dipole antenna connected to a two-conductor feed line adapted for connection to radio apparatus, a reflector parallel to said antenna and located forwardly thereof at a distance not substantially greater than 0.27 wave length, and a parabolic reflector associated with said antenna and located rearwardly thereof in such a manner that the effective center of radiation defined by the cooperation of said dipole antenna and said reflector lies approximately on the axis of said parabolic reflector at a distance from the vertex of said parabolic reflector equal approximately to an integral number of half-wave lengths, the integral number of half-wave lengths being chosen to bring said effective center nearest to the focus of said parabolic reflector.

2. A directive antenna system including a dipole antenna connected to a two-conductor feed line adapted for connection to radio apparatus, a reflector parallel to said antenna and located forwardly thereof at a distance not substantially greater than 0.27 wave length, and a parabolic reflector having a focal length approximately equal to an integral number of half-wave lengths

and located rearwardly of said antenna in such a manner that the effective center of radiation defined by the cooperation of said dipole antenna and said first named reflector lies at the focus of said parabolic reflector.

3. A directive antenna system including a dipole antenna connected to a two-conductor feed line adapted for connection to a radio apparatus, a reflector dipole parallel to said antenna and located forwardly thereof at a distance not greater than one-quarter wave length, and a parabolic reflector having a focal length approximately equal to an integral number of half-wave lengths and located rearwardly of said antenna in such a manner that the midpoint between the respective centers of said dipole antenna and said reflector dipole lies at the focus of said parabolic reflector.

4. A directive antenna system including a dipole antenna connected to a two-conductor feed line adapted for connection to radio apparatus, a reflector dipole parallel to said antenna and located forwardly thereof at a distance substantially less than one-quarter wave length, and a parabolic reflector associated with said antenna and located rearwardly thereof in such a manner that the midpoint between the respective centers of said dipole antenna and said reflector dipole is located approximately on the axis of said parabolic reflector and at a distance from the vertex of said parabolic reflector of approximately an integral number of half-wave lengths, the said integral number of half-wave lengths being so chosen as to bring said midpoint as near as possible to the focus of said parabolic reflector under the conditions herein defined.

5. A directive antenna system including a dipole antenna connected to a two-conductor feed line adapted for connection to radio apparatus, a reflector dipole parallel to said antenna and located forwardly thereof at a distance of approximately one-eighth wave length, and a parabolic reflector associated with said antenna having a focal length of approximately an integral number of half-wave lengths and located rearwardly of said antenna in such a manner that the midpoint between the respective centers of said dipole antenna and said reflector dipole lies at the focus of said parabolic reflector.

6. A directive antenna system including a dipole antenna connected to a coaxial-conductor feed line adapted for connection to radio apparatus, a sleeve choke mounted on the outer conductor of said feed line with its open end located near said dipole antenna but not close enough thereto to permit the occurrence of corona discharge, a reflector dipole parallel to said antenna and located forwardly thereof at a distance substantially less than one-quarter wave length and a parabolic reflector associated with said antenna and located rearwardly thereof in such a manner that said feed line passes through said parabolic reflector at the vertex of the said parabolic reflector and is supported at said vertex and further that the midpoint between the respective centers of said dipole antenna and said reflector dipole lies approximately on the axis of said parabolic reflector at a distance from said vertex equal to an integral number of half-wave lengths and at a distance from the focus of said parabolic reflector which is not greater than one-half wave length.

7. A directive antenna system including a dipole antenna having arms of bulbous shape connected to a coaxial-conductor feed line adapted for con-

nection to radio apparatus, a reflector dipole slightly longer than said dipole antenna, parallel to the axis of said antenna and located forwardly thereof at a distance substantially less than one-quarter wave length, a sleeve choke mounted upon the outer conductor of said coaxial feed line having its open end near said antenna but not so near thereto as to permit the occurrence of corona discharge in the operation of said system and a parabolic reflector associated with said antenna and located rearwardly thereof in such a manner that the midpoint between the respective centers of said dipole antenna and said reflector dipole is located approximately on the axis of said parabolic reflector at a distance from its vertex of approximately an integral number of half-wave lengths and at a distance from the focus of said parabolic reflector not greater than one-half wave length.

8. A directive antenna system including a dipole antenna having arms of bulbous shape connected to a coaxial-conductor feed line adapted for connection to radio apparatus, a reflector dipole longer than said dipole antenna, parallel to the axis of said antenna and located forwardly thereof at a distance substantially less than one-quarter wave length, a sleeve choke mounted on the outer conductor of said feed line with its mouth directed towards said antenna, a prospective vessel enclosing said dipole antenna, said reflector dipole and said sleeve choke and made of material essentially transparent to radiation in connection with which said antenna system is adapted to operate, the space enclosed by said vessel communicating with the space between the conductors of said coaxial conductor feed line, said vessel being adapted to maintain pressure in the neighborhood of said antenna, and a parabolic reflector associated with said antenna and located rearwardly thereof in such a manner that the midpoint between the respective centers of said dipole antenna and said reflector dipole is located approximately on the axis of said parabolic reflector at a distance from its vertex of approximately an integral number of half-wave lengths and at a distance from the focus of said parabolic reflector not greater than one-half wave length.

9. A directive antenna system including a dipole antenna connected to a coaxial-conductor feed line adapted for connection to radio apparatus, a reflector dipole parallel to said antenna and located forwardly thereof at a distance substantially less than one-quarter wave length, a vessel of material essentially transparent to radiation in connection with which said antenna system is adapted to operate, which vessel encloses said dipole antenna and said reflector dipole and is sealed to the outer conductor of said coaxial-conductor feed line, said vessel being adapted to maintain an internal pressure and having an extended neck adjacent to said outer conductor of said feed line, means mounted on said outer conductor of said feed line covering said extended neck in such a manner as to constitute a sleeve choke resonant at the frequency of operation of said antenna system and at the same time to secure mechanically the said vessel upon said outer conductor, and a parabolic reflector associated with said antenna and located rearwardly thereof in such a manner that the midpoint between the respective centers of said dipole antenna and said reflector dipole is located approximately on the axis of said parabolic reflector at a distance from its vertex approximately equal to an integral number of half-wave lengths and at a

distance from its focus not greater than one-half wave length.

10. In a directive antenna system which includes an antenna and a coaxial-conductor feed line connected to said antenna, a vessel enclosing said antenna and sealed to the outer conductor of said feed line made of material substantially transparent at the frequency of operation of said antenna adapted to maintain internal atmospheric conditions and having a neck extension adjoining said feed line and means mounted on the outer conductor of said feed line embracing said neck extension to define, in cooperation with said neck extension and a portion of said outer conductor, a choke resonant to the frequency of operation of said antenna and adapted to inhibit the formation of standing waves on the outside of said feed line, said means being also adapted to cooperate to secure said vessel in fixed relation to said feed line.

11. A directive antenna system including a dipole antenna connected to a two-conductor feed line adapted for connection to radio apparatus, a reflector dipole parallel to said antenna and located forwardly thereof at a distance substantially less than one-quarter-wave length, a protective vessel enclosing said antenna and said reflector dipole sealed to and mounted on said feed line, a support attached to said vessel for supporting said reflector dipole and for maintaining its position relative to said antenna, and a parabolic reflector associated with said antenna and located rearwardly thereof in such a manner that the midpoint between the respective centers of said dipole antenna and said reflector dipole lies approximately on the axis of said parabolic reflector at a distance from its vertex of approximately an integral number of half-wave lengths and at a distance from its focus not greater than one-half-wave length.

12. A directive antenna system including a dipole antenna connected to a coaxial conductor feed line adapted for connection to radio apparatus, a transformer in said feed line near said antenna for improving energy transfer between said line and said antenna which comprises a portion of said line of approximately a quarter-wave length having a characteristic impedance different from that of the rest of said line, a sleeve choke mounted on the outer conductor of said feed line with its open end located near said dipole antenna but not close enough thereto to permit the occurrence of corona discharge, a reflector dipole parallel to said antenna and located forwardly thereof at a distance substantially less than one quarter-wave length and a parabolic reflector associated with said antenna and located rearwardly thereof in such a manner that said feed line passes through said parabolic reflector at the vertex of the said parabolic reflector and is supported at said vertex and further that the midpoint between the respective centers of said dipole antenna and said reflector dipole lies approximately on the axis of said parabolic reflector at the vertex of the said vertex equal to an integral number of half-wave lengths and at a distance from the focus of said parabolic reflector which is not greater than one-half-wave length.

13. A directive antenna system including a dipole antenna having arms of bulbous shape connected to a coaxial-conductor feed line adapted for connection to radio apparatus, a transformer in said feed line near said antenna for improving energy transfer between said line and said antenna which comprises a portion of said line of

approximately a quarter-wave length having a characteristic impedance different from that of the rest of said line, a reflector dipole longer than said dipole antenna, parallel to the axis of said antenna located forwardly thereof at a distance substantially less than one-quarter-wave length, a sleeve choke mounted on the outer conductor of said feed line with its mouth directed towards said antenna, a protective vessel enclosing said dipole antenna, said reflector dipole and said feed choke and made of material essentially transparent to radiation in connection with which said antenna system is adapted to operate, the space enclosed by said vessel communicating with the space between the conductors of said coaxial conductor feed line, a support associated with said vessel for positioning and supporting said reflector dipole, and a parabolic reflector associated with said antenna and located rearwardly thereof in such a manner that the midpoint between the respective centers of the said dipole antenna and said reflector dipole is located approximately on the axis of said parabolic reflector at a distance from its vertex of approximately an integral number of half-wave lengths and at a distance from the focus of said parabolic reflector not greater than one-half-wave length.

14. A direct antenna system including a dipole antenna having arms of bulbous shape connected to a coaxial-conductor feed line adapted for connection to radio apparatus, a transformer in said feed line near said antenna for improving energy transfer between said line and said antenna which comprises a portion of said line of approximately a quarter-wave length having a characteristic impedance different from the rest of said line, a reflector dipole longer than said dipole antenna, parallel to the axis of said antenna and located forwardly thereof at a distance substantially less than one-quarter-wave length, a sleeve choke mounted on the outer conductor of said feed line with its mouth directed towards said antenna, a protective vessel enclosing said dipole antenna, said reflector dipole and said feed choke and made of material essentially transparent to radiation in connection with which said antenna system is

adapted to operate, the space enclosed by said vessel communicating with the space between the conductor of said coaxial conductor feed line, a support associated with said vessel for supporting and positioning said reflector dipole, and a parabolic reflector associated with said antenna and located rearwardly thereof in such a manner that the midpoint between the respective centers of the said dipole antenna and said reflector dipole is located approximately on the axis of said parabolic reflector at a distance from its vertex of approximately an integral number of half-wave lengths and at a distance from the focus of said parabolic reflector not greater than one-half wave length, said parabolic reflector having a focal length approximately equal to 0.3 times the diameter of said reflector.

15. A directive antenna system including a dipole antenna connected to a two-conductor feed line adapted for connection to radio apparatus, a reflector parallel to said antenna and located forwardly thereof at a distance not greater than one quarter wave length, and a parabolic reflector associated with said antenna and located rearwardly thereof in such a manner that the effective center of radiation defined by the cooperation of said dipole antenna and said reflector is located at a distance from the vertex of said parabolic reflector equal approximately to an integral number of half wave lengths, said integral number of half wave lengths being chosen to bring said effective center nearest to the focus of said parabolic reflector.

Certificate of Correction

Patent No. 2,486,620

November 1, 1949

LESTER C. VAN ATTA

It is hereby certified that error appears in the printed specification of the above numbered patent requiring correction as follows:

Column 4, lines 54 and 55, for "transfoarmer" read *transformer*; column 15, line 29, for the word "prospective" read *protective*; column 18, line 59, for "o fthe" read *of the*; line 64, strike out "the vertex of the" and insert instead *a distance from*; column 18, line 19, for "conected" read *connected*;

and that the said Letters Patent should be read as corrected above, so that the same may conform to the record of the case in the Patent Office.

Signed and sealed this 3rd day of July, A. D. 1951.
